UNITED STATES PATENT OFFICE.

GEORGE W. STEIN, OF LOS ANGELES, CALIFORNIA.

COMBINED SCRUBBING BRUSH AND SCRAPER.

Application filed April 17, 1922. Serial No. 553,586.

To all whom it may concern:

Be it known that I, GEORGE W. STEIN, a citizen of the United States, residing at Los Angeles, in the county of Los Angeles and State of California, have invented new and useful Improvements in Combined Scrubbing Brushes and Scrapers, of which the following is a specification.

My invention relates to a combination scrubbing brush and scraper, the brush being of any usual or preferred construction, and the scraping means comprising a scraping blade, and also a squeegee if so desired.

It is the principal object of the invention to provide a device of this character, wherein the scraping means may be swung into inoperative position upon the back of the brush, and the latter used in usual manner, or the scraping means may be swung into various operative positions projecting beyond the brush, and locked in such positions, for using both the brush and the scraping means.

The invention further provides a combination device as set forth, which is of relatively simple structure, capable of inexpensive manufacture, and effective in use.

With the foregoing and other objects in view my invention consists in certain novel features of construction and arrangement of parts that will be hereinafter more fully described and claimed and illustrated in the accompanying drawing, in which:

Fig. 1 is a top plan view of a combined brush and scraper of my improved construction, with the scraper in inoperative position.

Fig. 2 is a similar view showing the scraper in one of its operative positions.

Fig. 3 is a side elevation of the brush and scraper.

Figs. 4 and 5 are top plan views of a modified construction having a scraping blade and a squeegee in combination with the brush, and showing respectively, the scraping blade and squeegee in inoperative and in operative positions.

Fig. 6 is a transverse section on the line 6-6 of Fig. 5.

Figs. 7 and 8 are top plan views of a still further modification, and showing respectively, the scraping blade in inoperative and in operative position.

Fig. 9 is a transverse section on the line 9-9 of Fig. 8.

Referring by numerals to the accompanying drawing, and particularly to the construction illustrated in Figs. 1, 2, and 3, 10 designates a brush back, preferably of wood, and having a field of bristles 11 at one side, 60 forming a usual scrubbing brush.

A scraping blade 12 is mounted flat upon the top of back 10, and is pivoted thereto adjacent one corner of the blade as by the screw 13.

The blade is of such size, that when swung into inoperative position as shown in Fig. 1, it will lie within the outline of back 10, so as not to interfere with the use of the scrubbing brush, but when swung outwardly as shown in Fig. 2, or into other operative positions, as shown in dotted lines in Figs. 1 and 2, the scraper will present either its side or end edge as a scraping medium, to be used in conjunction with the 75 scrubbing brush for cleaning pots, kettles, and the like.

A stop shown as a screw 14 is positioned in back 10 beyond the scraper, and the opposite sides of the scraper may be notched as shown at 15, said notches and stop being so arranged relative to one another that when the scraper is swung to its operative positions shown in dotted lines in Figs. 1 and 2, the screw 14 will be engaged by one or the other of said notches to limit the swing of the scraper and hold the same in operative position.

The scraper may be also provided with apertures 16 suitably positioned, and adapted to receive a screw threaded into back 10, through one or the other of said apertures, when it is desired to more permanently fix the scraper in one of its various positions.

In the modified construction, shown in Figs. 4, 5, and 6, both a squeegee and a scraping blade are mounted upon the back 10 of the scrubbing brush, the scraper 12' being pivoted by screw 13' as previously described, for swinging movement into operative or inoperative position.

The squeegee comprises a metal strip 18 bent upon itself and adapted to clamp a projecting rubber strip 19. Rivets 20 are preferably employed for positively securing the rubber strip in position.

The squeegee extends along one side of the brush and is pivotally mounted at its inner edge, so that it may be swung back upon the brush back 10, when not in use,

or swung over and outwardly into operative position, with the rubber strip positioned beyond the side of the brush.

The pivotal mounting for the squeegee 5 comprises staples 21, received through the rear edge of the metal strip 18, and extending into the brush back. Washers 22 are disposed between the squeegee and back 10, at said washers, in order to space the 10 squeegee from the brush back, and thereby provide space for the scraper 12' to swing into inoperative position beneath the squeegee, as shown in Fig. 4.

A screw 23 having a laterally extending 15 head, is positioned in back 10 along side of the squeegee and adjacent its rear edge, said screw being adapted to be turned so as to disengage the squeegee when the latter is swung upon its pivot, or turned into locking 20 position with the lateral head of the screw overlying the squeegee, when the latter is in inoperative or operative position, as shown in Figs. 4 and 5, respectively.

In the construction as thus described, the 25 scraper 12' is preferably cut away at one side as shown at 25, in order to avoid one of the staples 21, when the scraper is swung into the operative position shown in dotted lines in Fig. 4, and the other side of the 30 scraper may be provided with a notch 15' which is adapted to be engaged by said staple, when the scraper is in the position shown in Fig. 5.

In the modification shown in Figs. 7, 8, 35 and 9, a squeegee is fixed in operative position at one side of back 10, and the scraper 12' is pivotally mounted as previously described.

The squeegee comprising the bent metal 40 strip 18 and projecting rubber strip 19 is mounted in operative position along one side of back 10, and is fixed in position by screws 28. Washers 22 upon the screws, space the squeegee from back 10 to permit

the scraper to swing beneath the squeegee 45 as previously described.

In this construction the scraper 12' is cut away at one side as heretofore mentioned and as shown at 25, in order to avoid one of the screws 28, when in its operative position shown in dotted lines in Fig. 8.

In the various forms of the invention, the back 10 may be provided with a tapering inclined aperture 30 adapted to receive a suitable handle, so that the device may be 55 employed for cleaning windows, transoms, and the like.

It will be noted that the improved device is a comparatively simple and inexpensive structure, and provides a convenient combination of scrubbing and scraping means, forming a handy and universal household article.

It will also be apparent that the implement is susceptible of minor changes in 65 construction, without departing from the spirit of the invention.

I claim as my invention:

1. A combination implement comprising a brush back and a scraper pivoted to said 70 back and adapted to be swung outwardly into operative positions, at either side or at one end of said brush back, or inwardly so as to overlie said back in inoperative position.

2. A combination implement comprising a brush back and a scraper pivoted to said 75 back and adapted to be swung outwardly into operative positions at either side or at one end of said brush back, or inwardly so as to overlie said back in inoperative position, said scraper having openings and means cooperating therewith to hold said scraper in a desired position.

In testimony whereof I have signed my 85 name to this specification.

GEORGE W. STEIN.
